Letters Patent No 494 Dated Aug. 31st 1852

The schedule referred to in these Letters Patent and making part of the same

To all whom it may concern:

Be it known that I, Samuel A. House of Mechanicville, in the County of Saratoga, and State of New York, have invented or produced a new and original design of parlor Stove front, which I call the "Pride of the North" and I do hereby declare that the following is a full and exact description of the same, reference being had to the annexed drawings making a part of this specification in which fig. 1. is a front view fig. 2. a sectional view taken at the line x, w, and fig. 3. a sectional view taken at the line y, z.

The ornamental design of my stove front consists in the arrangement of the scrolls (a a) one on each side; with the ornamental

caps (b) at the top, and in the mouldings (c e) around the sides and arch
of the fire place, together with the mouldings (d d) around the sunk panel
(e)

Having thus described my design of stove front,
what I claim as new and desire to secure by
Letters Patent, is, the ornamental design and configuration of stove front
the same as herein described, and represented in the annexed drawings.
